TELEVISION CABINET

Robert D. Budlong, Skokie, Ill., assignor to Zenith Radio Corporation, a corporation of Illinois

Application May 24, 1954, Serial No. 30,633

Term of patent 14 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Television Cabinet, of which the following is a specification, reference being made to the accompanying drawing forming a part hereof.

The single figure is a perspective view of a television cabinet showing my new design.

The side of the cabinet not shown is similar to that shown in the figure, and the rear of the cabinet is unornamented.

I claim:

The ornamental design for a television cabinet, substantially as shown and described.
